CLAIM

The ornamental design for a dispensing squeeze bottle, as shown and described.

DESCRIPTION

FIG. 1 is a diagrammatic perspective view of the dispensing squeeze bottle in full lines with a hand and pet dish shown in broken lines representing environmental association matter being for illustrative purposes only and forming no part of the claimed invention;

FIG. 2 is a front elevational view thereof;

FIG. 3 is a rear elevational view thereof, the left and right side elevational views being mirror images of the rear view;

FIG. 4 is a top plan view thereof; and,

FIG. 5 is a bottom plan view thereof.
